UNITED STATES PATENT OFFICE.

FRED N. THAYER, OF BINGHAMTON, NEW YORK.

SUPPORTING DEVICE.

1,084,504.

Specification of Letters Patent. Patented Jan. 13, 1914.

Application filed March 15, 1913. Serial No. 754,434.

To all whom it may concern:

Be it known that I, FRED N. THAYER, a citizen of the United States, residing at Binghamton, in the county of Broome and State of New York, have invented new and useful Improvements in Supporting Devices, of which the following is a specification.

This invention relates to supporting devices, and it has particular reference to an improved structure whereby window blinds and the like may be supported and manipulated while being painted.

One object of the invention is to produce a supporting device of simple and inexpensive construction which, when not in use may be knocked down for storage or transportation.

A further object of the invention is to produce a simple and efficient supporting device which may be readily adjusted for the purpose of supporting blinds of various dimensions.

A further object of the invention is to produce a supporting device including means whereby a blind may be supported in such fashion that it may be rotated to present either side uppermost.

With these and other ends in view, which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the appended claims may be resorted to when desired.

In the drawing:—Figure 1 is a side elevation of the device constructed in accordance with the invention. Fig. 2 is an end view of the same. Fig. 3 is a sectional detail view taken on the line 3—3 of Fig. 1.

Corresponding parts in the several figures are denoted by like characters of reference. The improved supporting device may be constructed of any suitable material or combination of materials such as wood and metal, but it has been found that it may be practically and efficiently constructed mainly of tubular iron such as ordinary gas pipe and joints or couplings whereby the pieces

of pipe are connected together. This construction has been selected for the purpose of illustration.

Bars or end members 1 are provided, each having sockets 2 at the ends thereof wherein legs or supporting members 3 are secured adjustably by set screws 4. The end members 1 are provided about midway between their ends with sleeves 5 for the accommodation of a connecting member 6 whereby said end members are spaced apart, the sleeves being provided with set screws 7 engaging the connecting member with which the end members are thereby adjustably connected. The sleeves 5 are provided with sockets 8 wherein uprights 9 are mounted and secured by set screws 10. Braces 11 may be employed to connect the uprights 9 with the connecting member 6, thereby producing a firm and rigid structure which may be readily disassembled or knocked down for storage or transportation.

The uprights 9 are provided at their upper ends with bosses or bearings 12 wherein shafts 13 and 13' are supported for rotation, one of said shafts being provided with a crank 14 whereby it may be manipulated. The shaft 13 having the crank 14 is provided with a cross bar 15 having prongs or barbs 16; a similar cross bar 15' having barbs 16' is mounted on the shaft 13' which slides or telescopes in its bearing; a spring 18 being employed to force the shaft 13' carrying the cross bar 15' in the direction of the cross bar 15 on the shaft 13. Mounted adjustably on one of the uprights 9 is a sleeve 19 having a supporting shelf or bracket 20.

In assembling the improved supporting device, the sleeves 5 of the end members are properly adjusted on the connecting member 6 to suit the dimensions of the blinds that are to be operated upon. To mount a blind in position for operation one end thereof may be supported edge-wise on the shelf or bracket 20 while being placed in engagement with the barbs 16 of the cross bar 15, the opposite end being held or supported by the operator while being placed in engagement with the barbs 16' of the cross bar 15' on the spring actuated shaft 13'. When thus mounted the blind may be rotated by means of the crank 14 about the axis of the shafts 13 and 13', and it may thus be presented in the most advantageous position to be painted, varnished, or otherwise deco-

rated. A suitable clamp 21 mounted on one of the uprights 9 may be used to engage the crank 14 for the purpose of holding the shafts and the blind supported by said 5 shafts temporarily against rotation.

Window blinds, while being painted, require to be frequently turned or otherwise manipulated in order to enable the painter to have access to all of the parts that are to 10 be covered. My improved supporting device provides means whereby a window blind may not only be securely supported, but whereby it may be turned or reversed as often as may be desired without touching 15 the parts to which paint has been applied.

What is claimed is:—

1. A supporting device of the class described including uprights having bearings, shafts supported for rotation in the bearings, one of said shafts being slideable and spring actuated in the direction of the other shaft, a sleeve on one shaft, barbed cross bars on said sleeve and on the opposed shaft, and a crank on one of the shafts.
- 20 2. A supporting device of the character described including uprights having bear-

ings at their upper ends, shafts supported for rotation in said bearings, clamping devices comprising barbed cross bars associated with the shafts, one of said cross bars 30 being resiliently supported, a crank connected with one of the shafts, and a shelf or bracket adjustable on one of the uprights.

3. In a supporting device of the class described, a frame including end members, a connecting member with which said end members are adjustably connected, legs detachably associated with the end members, uprights rising from the end members, and braces connecting the uprights with the connecting member; in combination with shafts supported for rotation on the uprights, one of said shafts being spring actuated in the direction of the other shaft, clamping members associated with the shafts, and a shelf 40 or bracket adjustable on one of the uprights.

In testimony whereof I affix my signature in presence of two witnesses.

FRED N. THAYER.
